UNITED STATES PATENT OFFICE.

HORACE H. TAYLOR, OF SAN JOSE, CALIFORNIA.

POWER-TRANSMITTING MECHANISM.

No. 811,258.

Specification of Letters Patent.

Patented Jan. 30, 1906.

Application filed January 11, 1905. Serial No. 240,642.

To all whom it may concern:

Be it known that I, HORACE H. TAYLOR, a citizen of the United States, residing at San Jose, in the county of Santa Clara, State of California, have invented certain new and useful Improvements in Power-Transmitting Mechanism, of which the following is a description, reference being had to the accompanying drawings and to the figures of reference marked thereon.

My invention relates to power-transmitting mechanism particularly adapted for use in connection with motor-vehicles, and has for its object to provide an arrangement of gearing which shall be simple in construction, comparatively inexpensive to build, and shall be convenient and certain in operation.

In motor-vehicles it is desirable to provide for driving the vehicle either ahead or to the rear at a high speed, moderate speed, or slow speed, as desired, and for shifting quickly from one speed to another and for quickly stopping or reversing. The gearing capable of providing for such different speeds and for so reversing ordinarily involves the use of a large number of parts, making it expensive in construction and liable to easily get out of order. In my invention the speed may be readily varied within considerable limits through the high, moderate, and slow speeds.

My invention consists in the construction and arrangement hereinafter set forth, and particularly pointed out in the claims.

Referring to the drawings, Figure 1 is a longitudinal sectional view of my improved power-transmitting mechanism. Fig. 2 is a plan view of the same, partly in section. Fig. 3 is a cross-sectional view.

In the drawings, 1 is the supporting-frame for the mechanism and in case the invention is used in connection with the driving mechanism of a motor-vehicle will be the frame of the vehicle.

2 is a frame pivoted or hinged to the supporting-frame 1 at 3 and is hereinafter referred to as the "hinged" frame. At its free end the hinged frame is provided with boxes or bearings 4, in which is journaled a shaft 5, having keyed thereon at one end a drum 6 and having at its other end a spur-gear 7. The drum 6 is provided on its interior with internal driving-faces 8 and 9 of different diameters which may act by friction only or may be provided with gear-teeth, and its hub 55 is provided with an extension 10, having a

tapered external driving-face 11. Arranged within the drum 6 is a friction or spur driving-gear 12, carried by a shaft 13. The driving-gear 12 has an outer driving-face 14 and an internal tapered driving-face 15. The driving-gear 12 and the drum 6 are so mounted, as hereinafter described, that by movement of one or the other, or both, the outer driving-face 14 of the driving-gear may be brought into contact or engagement with either of the internal driving-faces 8 or 9 of the drum 6 or its internal tapered driving-face 15 may be brought into engagement with the tapered driving-face 11 of the extension 10 of said drum. When a friction-drive is used, the driving-face 14 is preferably provided with a friction-surface 16, of rawhide or other non-metallic material affording a good friction-surface.

The shaft 13 is journaled in a bearing 17, carried by the frame 1, and is connected at its outer end with the fly-wheel 18 of the motor by a friction-clutch or in any convenient manner, as by flexible connection 19, the fly-wheel 18 being a part of the motor or other source of power used.

In order to permit of the movement of the driving-gear 12 and drum 6 necessary to bring the driving-face 14 into engagement with the internal driving-faces 8 or 9 or to bring the driving-face 15 into engagement with the driving-face 11, it is necessary to provide for swinging the shaft 5, carrying the drum 6, in a plane at right angles to its axis and to provide for movement of the driving-gear 12 longitudinally of the axis of its shaft. The swinging of the shaft 5 is effected by swinging the hinged frame 2 by means of lever 19, carried by rock-shaft 20, journaled in the frame and carrying at a point near the shaft 5 a lever-arm 21, the free end of which is connected by link 22 with the free end of the hinged frame 2. The lever 19 is provided with the usual spring locking-bolt 23, adapted to engage any one of the notches 24, formed in the fixed segment 25, at the center of which the rock-shaft 20 is journaled, so that the shaft 5, with the friction or gear drum 6, may be locked at the proper elevations, as desired.

The link 22 consists of a pair of flexible or jointed arms 27, connected at their upper ends to the lever-arm 21 and at their lower ends connected to the hinged frame 2. The pivots 28, which connect the upper and lower members of the arms 27, extend into a slot 29

in a link 30. Extending through the slot 29 between the arms 27 is a rod 31, carrying a double-armed cam 32. To the rod 31 is secured an operating-lever 33, preferably adapted when the device is to be used on a motor-vehicle to be actuated by the foot of the operator to rock the rod 31 and cause the cam-arms 32 to act against the arms 27 to spread them, and thus by shortening the length of the link cause the hinged frame 2 to be raised slightly, raising the shaft 5 and drum 6 and pressing the internal driving-face of the drum 6 against the periphery of the driving-gear 12, increasing the frictional contact, and, if used on a friction-drum, by lessening the slip, increasing the speed of the vehicle.

In order to permit of the movement of the driving-gear 12 longitudinally on its shaft 13, it is connected to the shaft by a spline 35 and is journalled in a bearing 36, carried by a slide 37, movable on a guide 38, secured to a transverse bar 39 of the frame 1. The movement of the slide 37 is effected by means of a sleeve 40, adapted to rock on a rod 41, secured at its ends to the frame 1, the sleeve carrying at one end an arm 42, having at its end a pin 43, engaging a slot 44 in the slide 37 and having at the other end an arm 45, connected by a link 46 with a lever 47, suitably pivoted in the frame 1.

Beside the gear 7, on its rear end the shaft 5 is also provided intermediate its ends with a gear 49. Parallel with the shaft 5 is a shaft 50, carried in bearings 51, secured to the hinged frame 2, and on the shaft is slidingly carried a sleeve 52, having at one end a gear 53, adapted to be engaged by the gear 49, and at its other end an internal gear 54, adapted to engage the gear 7 on shaft 5. Between the gear 53 and internal gear 54 the sleeve is provided with a flanged collar, within which work the arms of a forked lever 56, pivoted to a fixed portion of the frame 2 and connected by a link 58 to any convenient shifting means. At its rear end the shaft 50 is connected by any convenient form of universal joint 59 to a shaft 60, extending to the rear axle of the vehicle and connected thereto by any convenient form of gearing. (Not necessary to be shown.)

When it is desired to drive the vehicle ahead at slow speed, the lever 19 is moved to raise the shaft 5 and drum 6 to the position shown in Fig. 1, the lever 47 being operated to bring the periphery of the driving-gear 12 into mesh or frictional engagement with the internal face 8 of the drum, power being transmitted from the shaft 13 through the gear 12, the drum 6, shaft 5, gear 49, gear 53, shaft 50, universal joint 59, and shaft 60 to the axle.

When increased speed is desired, the shaft 5 and drum 6 are lowered slightly and the driving-gear 12 is pushed rearward to bring its periphery into mesh or frictional engagement with the internal face 9 of the drum, the

power being transmitted as before. When it is desired to further increase the speed, the shaft 5 and drum 6 are further lowered until the axis of the shaft 5 is in line with the axis of shaft 13, and the gear 12 is pushed rearwardly until its internal face 15 engages the face 11 of the hub of the drum 6, the power being transmitted as before. By operating the lever 33 when the driving-gear is in engagement with the internal face 8 or the internal face 9 of the drum the pressure of the driving-gear against the drum may be varied, thus regulating the slip and within limits varying the speed. When it is desired to drive the vehicle rearward, the sleeve 52 is shifted to move the gear 53 out of engagement with the gear 49 and to bring the internal gear 54 into engagement with the gear 7. In order to stop the vehicle, it is only necessary to operate the lever 47 or to move the gear 12 forward out of frictional contact with the part of the drum 6 with which it may be in contact at the time without moving the shaft 5 and drum, and, conversely, in starting, the drum being in the position desired, it is necessary only to operate the lever 47 to move the gear 12 into engagement with the drum.

The internal face 15 of the gear 12 may, if preferred, be provided with teeth to engage corresponding teeth on the hub of the drum 6. 95

It will of course be understood that I do not desire to be limited to the precise construction and arrangement shown, nor do I desire to be limited to the use of the friction contact alone, but can use gearing on the driving-pulley 12 and teeth internally in the drum 6, nor is it limited to use in connection with motor-vehicles, as it is evident that it may be used for other purposes.

Having thus described my invention, what I claim, and desire to secure by Letters Patent, is—

1. In a power-transmitting mechanism, the combination with a driving-gear having external and internal driving-faces, of a drum having an internal face adapted to be engaged by the external driving-face of the gear, and also an external face adapted to be engaged by the internal driving-face of the gear.

2. In a power-transmitting mechanism, the combination with a driving-gear having an external and an internal driving-face, of a drum having a plurality of internal faces each adapted to be engaged by the external driving-face of the gear, and also an external face adapted to be engaged by the internal driving-face of the gear, means for shifting the drum in a direction transversely to its axis and means for shifting the driving-gear longitudinally of its axis.

3. In a power-transmitting mechanism, the combination with a driving-gear having a peripheral driving-face, of a drum having a plurality of internal faces, each of which is

adapted to be engaged by the peripheral driving-face of the driving-gear, a shaft on which the drum is secured, a hinged frame carrying bearings in which the shaft is journaled and means for raising and lowering the free end of the hinged frame.

4. In a power-transmitting mechanism, the combination with a driving-gear having a peripheral driving-face, of a drum having a plurality of internal faces, each of which is adapted to be engaged by the peripheral driving-face of the driving-gear, a shaft on which the drum is secured, a hinged frame carrying bearings in which the shaft is journaled, means for raising and lowering the free end of the hinged frame and means for moving the driving-gear longitudinally of its axis.

5. In a power-transmitting mechanism, the combination with a driving-gear having a peripheral driving-face, of a drum having an internal face for engagement with the driving-face of the gear, means for raising the drum to bring its internal face into contact with the driving-face of the gear, and independently-operated means for varying the contact between the gear and the drum.

6. In a power-transmitting mechanism, the combination with a driving-gear having a peripheral driving-face, of a drum having an internal face, for engagement with the driving-face of the gear, means for raising the drum to bring its internal surface into contact with the driving-face of the gear, comprising a lever-arm and a connecting-link, and means for varying the effective length of

the link to vary the contact between the gear and the drum.

7. In a power-transmitting mechanism, the combination with a driving-gear having a peripheral driving-face, of a drum having an internal face, for engagement with the driving-face of the gear, means for raising the drum to bring its internal face into contact with the driving-face of the gear comprising a rock-shaft provided with an operating-lever and with a lever-arm and connecting-link, means for locking the operating-lever and means for varying the effective length of the link to vary the contact between the gear and drum.

8. In a power-transmitting mechanism, the combination with a driving-gear having a peripheral driving-face, of a drum having an internal face for engagement with the driving-face of the gear, means for raising the drum to bring its internal face into contact with the driving-surface of the gear comprising a rock-shaft provided with an operating-lever and with a lever-arm and connecting-link, the latter consisting of a pair of flexible arms, means for locking the operating-lever and means for spreading the flexible arms of the link to vary the contact between the gear and drum.

In testimony whereof I affix my signature in presence of two witnesses.

HORACE H. TAYLOR.
